UNITED STATES PATENT OFFICE.

ERNE A. MORSE, OF LIBERTY, NEBRASKA.

DELIVERY SYSTEM AND APPARATUS THEREFOR.

No. 909,925.

Specification of Letters Patent.

Patented Jan. 19, 1909.

Application filed April 28, 1903. Serial No. 423,166.

To all whom it may concern:

Be it known that I, ERNE A. MORSE, a citizen of the United States, residing at Liberty, in the county of Gage and State of Nebraska, have invented a new and useful Delivery System and Apparatus Therefor, of which the following is a specification.

This invention relates to a delivery system and the apparatus therefor.

10 The invention has special relation to delivery systems whereby goods, messages, and the like, may be sent from a central station to various stations, as, for instance, from a central station, located in a town, to farm houses along roads, and so forth.

One object of the invention is to provide an improved system for the purpose described.

20 A second object of the invention is to provide an improved car for such system.

A third object of the invention is to provide an improved means for supporting overhead tracks in such a system.

25 A still further object of the invention is to provide improved means for stopping the car at any predetermined point in the system.

The invention comprises, in general, a central station, a plurality of overhead tracks 30 leading therefrom to desired points, a suitable car arranged to run on one of said tracks, and suitable means located at a predetermined point to stop said car when desired.

35 The invention consists further in certain novel details of arrangement and combinations of parts, hereinafter fully described, illustrated in the accompanying drawings, and specifically set forth in the claims.

40 In the accompanying drawings, like characters of reference refer to like parts throughout the several views, and Figure 1 is a general perspective view of a delivery system constructed in accordance with this invention. Fig. 2 is a side elevation of a portion 45 of one of the tracks and parts of the station apparatus showing a car suspended from the track. Fig. 3 is a detail perspective view of the arrangement of the track and supports at a station. Fig. 4 is an end view of the tracks at a station showing the manner of approaching the station platform. Fig. 5 is a detail of one of the supporting rollers or wheels of a car.

50 55 In the perspective view of the entire system shown in Fig. 1, the central station is in- dicated by the letter A. It will be observed that from this central station extends a number of pairs of tracks, each track comprising two wires. As there is no ground connection between the motor on the car and the wire which supports this car, it is necessary that there should be two wires to form the circuit.

60 In Fig. 1 the incoming tracks are designated by the letter B. In the same figure the outgoing tracks are designated by C. At D is shown a station, and at E is shown a car coming in, while at F is shown an outgoing car.

65 While the station A is here shown as a platform simply, it is to be understood that the same may be in any convenient location, such as a building or other structure specially designed for the purpose. It is further to be observed that while the tracks are here shown as substantially radial, they may all come into one side of a building, or the like, this arrangement being merely a 70 mechanical detail.

75 It is, of course, plain that the wires forming the tracks are to be connected to some suitable source of electric power. This, however, is not here shown, as it forms no part of the present invention.

80 Each track or circuit comprises a supporting wire 10 and a return circuit wire 11, these wires being arranged parallel throughout the circuit.

85 Each local station comprises a pole 12 whereon is mounted a platform 13 approached by means of suitable winding stairs 14 arranged around the pole. The wires forming the tracks are supported only at the stations, these supports comprising bars 15 supporting the wires 10 and bars 16 supporting the wires 11. In addition to the supports for the wires at each of the stations, there is a frame 17 whereupon is mounted a pair of parallel racks 18 placed 90 on either side of the wires 10 and arranged to have the center portion extend above the supports 15, while the ends pass downward to pass below the wires 10.

95 100 In addition to the above described station apparatus, there is mounted on the pole a quadrant 19.

105 The car is preferably made somewhat boat-shaped with a forward, pointed end. The body of the car is indicated by the numeral 19'. Upon this body are held standards 20 and 21. Mounted for rotation in 110

the upper part of each of these standards is a wheel 22 provided with a grooved periphery 23 arranged to run on one of the wires 10. This groove is further provided with laterally extending annular flanges 24, for purposes to be hereinafter described. The wheel 22 that is mounted in the standard 21 is provided with an insulating bushing 25. This wheel is keyed or otherwise fixed to a shaft 26 which is mounted in the standard 21 by means of suitable insulating bearings 27 and 28. Upon the shaft 26 is fixed a sprocket wheel 29. Mounted on the insulating bearings 28 is a plate of copper, or the like, as indicated at 30. This plate 30 is provided with a suitable binding post 31 whereto is connected a wire 32. The construction of the wheel 22 that is carried in the standard 20 is precisely similar to that just described, with the exception that there is no sprocket 29 on the shaft of that wheel, and the shaft is consequently made shorter. The wires 32 are led to a switch 33 mounted, on what may be termed, the deck of the carrier. A wire 34 leads from the switch to a motor 35 located in any desired position within the carrier. From the motor 35 the circuit continues over a wire 36 to a trolley arm 37 pivotally connected to the carrier and arranged to be normally held in contact with the wires 11 by a spring 38. The trolley 37 is provided with a usual form of wheel, as indicated at 39.

Upon the motor 35 is held a sprocket or other drive wheel, as indicated at 40, and a sprocket chain, or the like, 41 serves to connect the sprockets 29 and 40, and thus to actuate the car when the motor rotates. The switch 33 is provided with an operating handle 42 and with a stop 43. When the switch is in position so that the circuit is complete, the operating handle 42 is arranged so as to be in a position substantially perpendicular to the body of the carrier. This is best seen in Fig. 2, and in the same figure the dotted line position of the switch represents the limit of movement of the operating handle. It is to be observed that this switch must be of heavy enough construction to act as a stop for the carrier. Mounted upon the quadrant 19 previously described is a latch lever 44. This lever is arranged so that it may be operated as shown in Fig. 4 and lie in the path of the operating handle 42 of the switch. It will be obvious that as the car goes past the point at which the lever 44 is situated, the lever will contact with the operating handle 42, open the switch and stop the car.

In order to minimize the danger of the car leaving the wire, there is mounted on the standards 20 and 21 a lever 45 on which is pivotally mounted a wheel 46 provided with a peripheral groove. The wheel 46 is held immediately below the wheel 22, so that the

wire end is closely embraced between the wheel 22 and the wheel 46. It is obvious that the wheel 46 must be provided with some insulating means, but as any means may be used for this purpose, the same has not been detailed. A spring 47 normally holds the wheel 46 tight up against the wire, but under certain conditions now to be described, the spring permits the wheel to move towards the body of the carrier and away from the wheel 22. When the car approaches a point at which the wires are supported, the flanges 24 of the wheels 22 will contact with the spaced rails 18. The entire device will then be caused to ride along the arcuate surface of these rails while at the same time the wheel 46 will continue to run under the wire 10. In this manner the device permits a separation of the wheels so that the bars 17 and 15 may be passed.

It will be seen that, in order to complete the electric circuit, some form of contact is necessary between the wheel 22 and the plate 30, and for this purpose there is provided a spiral spring 48.

In the operation of the device, let it be supposed that a customer living in the country desires to obtain goods from a town. The customer notifies the merchant in any manner, as by telephone or writing, as to the goods he desires. The merchant then either sends the goods to the central station or to the nearest local station. If the goods are sent to the local station, they are placed in the next incoming car with the proper directions affixed. This car carries them to the central station and the attendant at that station transfers the goods to the outgoing car on that branch whereon the purchaser is located. The purchaser in the meanwhile has thrown the latch lever at his station in such manner as to stop the car. The goods having been placed in the car, the switch is closed and the car started on the out-going track. On arriving at the station, the latch lever operates to open the switch and thus stop the car in the manner heretofore described. The purchaser observing the car at rest at his station then ascends to the platform by means of a winding stair and removes the goods. Should there be goods in the car intended for a point, or points, beyond said station, he then pushes the car beyond the station, first lifting the latch lever and closing the switch. The car then resumes its journey. Should, however, the car be empty, when arriving at the station, of all goods except those for the purchaser, he removes the car from that track, turns it around and places it on the in-going track, closes the switch and starts the car on its return.

It is obvious that letters and orders may be sent in from the outlying stations to the central, and distributed to the various nur-

chasers in the town by means of the in-going cars. It is also obvious that when it is desired to send parcels to people on the same line, or branch, it is merely necessary to place the car on the track, close the switch, and start it on its journey, notifying the party for whom it is intended by phone, or in any other suitable manner.

If it is desired, the goods receptacle in the car may be provided with a lock, and keys may be distributed to the parties using the system. In this manner it would be impossible for a stranger to stop the car and remove goods therefrom.

15 It will be plain that the incoming and out-going tracks have a loop at the extreme end thereof, so that the cars turn without the intervention of any person.

Other and various uses of this device will 20 also be plain.

Having thus described the invention, what is claimed is:—

1. In a delivery system, a wire, a support for said wire extending laterally therefrom, 25 a car comprising a body portion having wheels mounted thereon to support said car on said wire, other wheels mounted on the car to hold the first wheels from displacement from said wire, and means carried on and adjacent said supports to separate the first and second mentioned wheels and permit the car to pass said supports.

2. In a delivery system, a wire, a support for said wire extending laterally therefrom,

a car comprising a body portion having 35 wheels mounted thereon to support the car, levers mounted on the car, springs normally pressing said levers toward said wheels, other wheels carried on said levers to hold the first wheels from displacement from said 40 wire, and means carried on and adjacent said supports to separate the wheels and permit the car to pass the supports.

3. In a delivery system, a wire, a support for said wire extending laterally therefrom, 45 a car comprising a body portion having wheels mounted thereon provided with peripheral flanges, said wheels being arranged to support said car on said wire, a pair of spaced tracks extending from a 50 point below said wire over said supports to a second point below said wire and adapted to receive the flanges of said wheels, levers mounted on said car, wheels mounted on said levers to hold the first wheels from displacement from said wire, and springs supporting 55 said levers and normally forcing said wheels toward each other, said springs and track constituting a means for separating said wheels and permitting the car to turn the 60 support.

In testimony that I claim the foregoing as my own, I have hereto affixed my signature in the presence of two witnesses.

ERNE A. MORSE.
